(57) **CLAIM**

The ornamental design for a tubing clip, as shown and described.

DESCRIPTION

FIG. 1 is a first perspective view of the tubing clip of the present invention.

FIG. 2 is a second perspective view of the tubing clip of the present invention.

FIG. 3 is a front view of the tubing clip of the present invention.

FIG. 4 is a rear view of the tubing clip of the present invention.

FIG. 5 is a left-side view of the tubing clip of the present invention.

FIG. 6 is a right-side view of the tubing clip of the present invention.

FIG. 7 is a top view of the tubing clip of the present invention; and,

FIG. 8 is a bottom view of the tubing clip of the present invention.

The view labels used herein to denote, front, rear, left-side, right-side, top and bottom views are for convenience only and should not be interpreted as limiting the orientation of the tubing clip.

1 Claim, 7 Drawing Sheets
